UNITED STATES PATENT OFFICE.

FREDERICK E. KOHLER, OF CANTON, OHIO.

DESIGN FOR A LAWN-RAKE HEAD.

SPECIFICATION forming part of Design No. 28,812, dated June 7, 1898.

Application filed October 31, 1896. Serial No. 610,765. Term of patent 7 years.

To all whom it may concern:

Be it known that I, FREDERICK E. KOHLER, a citizen of the United States of America, residing at Canton, in the county of Stark, in the State of Ohio, have invented and produced a new and original Design for Lawn-Rake Heads, of which the following is a specification, reference being had to the annexed drawing, forming a part thereof, wherein the figure is a perspective view of a complete lawn-rake head, showing my new design.

As shown in the drawing, the leading or material feature of my design consists of a rake-head bar 1, produced from a metal plate of the desired length bent or formed in cross-section into polygonal form, producing in completed cross-section contour a "keystone" shape, with the end 5 of the form directed or placed to the front and the sides 3 4 inclined or placed in opposite directions therefrom and having the head 6 closed and rounded or

curved outward in contour, as shown in the drawing.

From the middle of the rake-head bar projects the round handle-socket, as shown, and through the rake-head bar are projected the desired number of U-shaped teeth 2, curved forwardly transversely to the bar, as shown in the drawing.

Having described my invention, what I claim as new, and desire to secure by Letters Patent, is—

The design for a lawn-rake head, as herein shown and described.

In testimony whereof I sign this specification, in the presence of two witnesses, this 20th day of October, 1896.

FREDERICK E. KOHLER.
